BOILER FEED CHECK VALVE

Reuben F. Davis, Kirby T. Penick, and Arthur J. Penick, Houston, Tex.; said Davis assignor to Kirby T. Penick and Arthur J. Penick

Application March 8, 1937, Serial No. 129,550

2 Claims. (Cl. 251—121)

This invention relates to a check valve for a combination boiler feed check and stop valve mechanism.

An object of the invention is to provide a check valve in a unitary construction of the character described, which is specially applicable to the feed water pipe of a boiler whereby water may be fed to the boiler as required to maintain the proper water level and whereby the back-flow of water or steam from the boiler will be prevented, with a stop valve embodied in the construction whereby the feed water pipe may be completely closed.

It is a further object of the invention to provide valve mechanism of the character described wherein the check valve casing and stop valve casing are formed as a unitary structure.

It is a further object of the invention to provide in a combined valve mechanism of the character described a novel assembly of valve seat and valve cage mounted in the check valve casing in a novel manner whereby the parts are rendered readily accessible for repairs and replacements.

The invention embodies certain improvements over that type of boiler feed check valve described in our co-pending application executed of even date herewith.

With the above and other objects in view the invention has particular relation to certain novel features of construction, operation and arrangement of parts, an example of which is given in this specification and illustrated in the accompanying drawing wherein:

Figure 1 shows a sectional view taken on the line 1—1 of Figure 2.

Figure 2 shows a sectional view taken on the line 2—2 of Figure 1 and Figure 3 shows a plan view of the valve mechanism as mounted in the water feed pipe of a boiler, showing also the boiler, pumps and connections.

Referring now more particularly to the drawing wherein like numerals of reference designate the same parts in each of the figures, the numeral 1 designates the check valve casing which is cylindrical in form and has the inlet connection 2 to which the feed pipe 3 is connected. The feed pipe 3 leads from the manifold 4 which in turn is connected with the pumps 5 by means of the delivery pipe 6. The valve casing 1 has an inside annular shoulder 7 on which the external rib 8 of the annular valve seat 9 rests. The flow of liquid through the seat 9 is controlled by the upwardly opening ball valve 10 which is confined by the valve cage 11. This

cage is of openwork construction as shown in Figure 1 and its lower end surrounds the valve seat and rests on the rib 8. The crown of the cage 11 is formed with a conical-shaped upwardly extending projection 12.

Screwed into the upper end of the casing 1 is the crown plug 13 which is concavo-convex in general contour and whose under side is formed to conform to the shape of and to fit closely against the projection 12 whereby the cage and valve seat are clamped securely in place. The upper end of the crown plug is formed with an extension 14 to receive a wrench whereby the plug may be screwed into place or unscrewed.

Screwed into the upper end of the casing 15 is a cap 15 which encloses and is spaced from the crown plug 13. The plug 13 has a duct 16 therethrough provided for the passage of air or water from the space above the plug, into the space beneath the plug when the cap 15 is screwed into place.

Formed integrally with one side of the casing 1 there is a cylindrical stop valve casing 17 having the connection 18 and leading from this connection there is a pipe 19 which enters the boiler.

Within the stop valve casing and aligned with the connection 18 there is a valve seat 20.

A bonnet 21 is screwed into the stop valve casing 17 in alignment with but spaced from the seat 20. This bonnet contains a stuffing box comprising the packing 22 and the gland 23, abutting the outer end of the packing and retained in place by the cap screw 24 which is screwed onto the bonnet and abuts the outer end of the gland. A valve stem 25 extends axially through said stuffing box and bonnet and has a hand wheel 26 on the outer end thereof. The stem 25 has a threaded connection with the bonnet and a swivel connection with the tapered stop valve 27 which is mounted on the inner end thereof in any suitable manner. The casings 1 and 17 are connected by a passageway 28 leading from the former into the latter.

Normally the stop valve 27 will be in open position and upon operation of the pumps 5 water will be forced into the manifold 4 and thence through the pipe 3 past the valve 10 and through the passageway 28 into the casing 17 and thence out through the seat 20 and through the pipe 19 into the boiler. When the pumps are stopped the check valve 10 will seat to prevent the back-flow of water or steam.

If for any reason it should be desired to close the pipe 19, the stem 25 may be appropriately

turned to seat the valve 27 against the seat 20. Repairs or replacements may then be made to the check valve mechanism.

The drawing and description disclose what is now considered to be a preferred form of the invention by way of illustration only, while the broad principle of the invention will be defined by the appended claims.

What we claim is:

- 10 1. In a combination boiler feed check and stop valve mechanism; a check valve comprising a tubular casing having an inlet connection at one end and a lateral opening, an annular valve seat in the casing between the connection and opening, a valve on said seat, a valve cage on the seat limiting the range of movement of the valve, a projection on the cage, a crown plug screwed into the end of the casing opposite said connection and having a concavo-convex contour 15 and whose central portion of the underside is formed to conform to the shape of and to fit closely against said projection, the outer end of the crown plug being formed with an extension projecting beyond the casing and adapted to 20 receive a wrench and a cap screwed into the end 25

of the casing and spaced from the crown plug.

2. In a combination boiler feed check and stop valve mechanism; a check valve comprising a tubular casing having an inlet connection at one end and a lateral opening, an annular valve seat in the casing between the connection and opening, a ball valve on said seat, a valve cage having a closed end and an open end, said open end positioned on the seat and the closed end limiting the range of movement of the valve, a 10 projection on the closed end of the cage and located on the longitudinal axis of said cage, a crown plug screwed into the end of the casing opposite the said connection having a concavo-convex contour and whose underside central portion is formed to conform to the shape of and to fit closely against said projection, the outer end of the crown plug being formed with an outwardly projecting extension adapted to receive a wrench and a cap screwed into the end of 20 the casing and spaced from the crown plug, said crown plug having a duct therethrough.
